UNITED STATES PATENT OFFICE.

JULIEN PUVREZ, OF LILLE, FRANCE, ASSIGNOR TO HIMSELF AND NARCISSE PIGEON, OF NEW YORK, N. Y.

APPARATUS FOR MALTING CEREALS.

SPECIFICATION forming part of Letters Patent No. 254,374, dated February 28, 1882.

Application filed March 10, 1881. (No model.) Patented in France March 15, 1880.

To all whom it may concern:

Be it known that I, JULIEN PUVREZ, of Lille, France, have invented a new and useful Improvement in Apparatus for Malting Cereals, 5 of which the following is a specification.

This invention relates to certain new and useful improvements in apparatus for germinating and drying malt, whereby the malt is obtained in a better state in a much shorter 10 time and more economically than with the devices in use at present.

These improvements will first be described in connection with the drawings, and then pointed out in the claims.

15 In the accompanying drawings, Figure 1 is a plan view of my improved malt-chamber, showing the several modifications of the germinating and drying floor. Fig. 2 is a longitudinal sectional elevation of the same. Fig. 3 is 20 a cross-sectional elevation of the same. Fig. 4 is a longitudinal elevation of the refreshing and moistening chamber of my improved malt-house, showing parts broken out to show the construction.

25 Similar letters of reference indicate corresponding parts.

The floor of the malt-chamber A is about 30 five to six inches above the ground, and is formed of a series of strips, B', of wood and perforated metal strips B², which are arranged alternately, as shown in Fig. 1. The advantage of this alternate arrangement of wooden and metallic strips is that it prevents a too rapid distribution of heat, and prevents the 35 malt from being too quickly heated.

A ventilating-chimney, G, is located at the end of the ventilating-channel, and is provided with a small furnace for creating a draft. The walls D of the ventilating-channel E are provided with apertures I, which increase in size 40 from that end of the channel E provided with a ventilating-chimney, G, toward the other end, for the suction is much greater at the end near the chimney, and therefore smaller apertures 45 I will answer at this end.

The steeped grain is placed upon the floor of the malt-chamber, about twelve to fifteen inches high, and the ventilating or drying air passes through this layer of grain and through the 50 slots or perforations in the floor of the malt-

chamber, and then passes through the apertures I in the ventilating-channel E and the chimney G, as is indicated by the arrows. But it is necessary that the ventilating-air that passes into the malt-room shall be moist and 55 fresh—that is, contain a quantity of ozone—and for this reason one or two moistening and refreshing chambers, J, are arranged at the end of the malt-chamber opposite to the ventilating-chimney G. A water-tube, K, with 60 small perforations on top, passes through the top of the chambers J, and through these perforations of the tube K the water spouts upon a plate, W, directly above the tube K, whereby the water is atomized and converted into 65 spray. From this plate, W the water runs down a series of strips of cloth or linen, M, suspended from a frame, L. These strips of cloth may be replaced by linen sheets or pieces of 70 cord or rope. From the lower ends of these cords, ropes, or sheets M the water drops upon a quantity of sponges, N, on a perforated shelf, O, in the bottom of the chamber J, and from this shelf the water drops upon the sponges N' 75 on the next lower shelf, O', and so from one shelf upon the other. The water is thus spread 80 upon a vast surface, and the air which enters the chamber J through the bottom aperture, P, and leaves it through the upper aperture, P', will be saturated with moisture when it enters 85 into the malt-house through this upper aperture, P; but the air will not only have absorbed moisture; it will also be slightly impregnated with ozone, and will be cooled. Cooled fresh air which is moistened and is ozonized 90 greatly facilitates the germinating of the cereals.

The moisture-chambers J are provided with vertical openings Q, extending from top to bottom on the front side, and these openings 95 are closed by means of sliding or swinging shutters Q'. These openings are provided to permit the quantity of sponges and the strings or strips M to be regulated and kept in proper order.

A portable sheet-iron stove, R, which is covered with some non-conducting material, can be connected with the malt-chamber for partially drying the malt in the same room in which it is germinated. This stove R is pro- 100

vided with a perforated horizontal plate, S, some distance above the fire, to prevent sparks and cinders from entering into the malt-room. As malt requires a certain quantity of fresh air 5 while drying, an aperture, T, is provided in the stove directly above the plate S, and through this aperture the fresh cool air enters.

A series of plates, U, are suspended vertically in the upper part of the stove R, and as 10 the cold and hot air pass up between these plates, they will be subdivided into so many layers, and will be thoroughly mixed above these plates. The warm air from the stove R also enters into the malt-room on top.

15 The operation in the malt-germinating chamber is as follows: The steeped grain is placed upon the perforated or slotted floor of the malt-house A, about twelve to fifteen inches deep. The air passes into the moistening-chamber J at P, passes into the malt-germinating chamber at P' through the moistened grain, through the apertures I I into the channel E, and up through the chimney. After the grain has germinated sufficiently, which, according to 20 circumstances, may require from six to ten days, it is brought into the kiln to be dried.

I am aware that a malting apparatus has been provided with a perforated bottom in the malt-chamber, a ventilating-channel beneath 25 it, a ventilating-chimney at one end, and a

moistening-chamber at the other end of channel; but

What I claim as new, and of my invention, is—

1. In a malt-chamber, the floor constructed, substantially as herein shown and described, 35 with alternating strips of wood and of perforated metal, as and for the purpose set forth.

2. The moisture-chambers J, provided with vertical openings Q, extending from top to bottom on the front side, whereby the sponges 40 may be regulated, as described.

3. In a malt-chamber, the combination, with the air refreshing and moistening chamber, of the perforated tube K, and of the atomizing-plate W arranged above it, substantially as 45 herein shown and described, and for the purpose of atomizing the water, so that the air that passes through the chambers J J will be slightly impregnated with ozone.

4. In a malt-chamber, the combination, with 50 the air refreshing and moistening chamber, of the water-tube K, the atomizing-plate W, the cloth strips M, and the sponges N, substantially as herein shown and described, and for the purpose set forth.

JULIEN PUVREZ.
